RECORD CARD WITH SELECTIVE CONDUCTIVE MARKS

William H. Wolowitz, Washington, D. C.

Application June 5, 1951, Serial No. 230,047

6 Claims. (Cl. 235—61.12)

1

This invention relates in general to improvements in record cards and sheets which are provided with electrically conductive sensing marks for controlling the operation of statistical machines, and is directed to the provision of an improved article of this nature and an improved method for providing such conductive marks upon the surface of a record card or sheet.

The invention deals, more particularly, with improvements in the preparation of record cards and sheets of this character which are provided in quantity with preformed conductive marks or spots at selected locations for predetermined applications and uses. The present application is a continuation in part of prior copending application Serial Number 124,713 filed October 31, 1949, and issued as United States Patent Number 2,557,022 on June 12, 1951.

In the provision of sensing marks with conducting graphite in the form of ink, such marks frequently are not uniform in their conductivity and, therefore, when sensed by contacting brushes or wipers, are unreliable as current conductors between such wipers. One of the principal reasons for this insufficiency resides in the fact that the oil or other fluid that is mixed with the graphite to provide any such ink necessarily detracts from the effectiveness of the graphite and otherwise increases the resistance of the colloidal graphite to electrical conductivity which causes unreliable sensing operations, as aforesaid. Moreover, in the handling of tabulating cards in which ink is used to form the conductive marks, the ink even when supposed to be dry, usually has a decided tendency to smear or smudge beyond the specific area of a sensing mark onto an adjoining area and thus cause inaccurate and undesired sensing operations.

A primary object of this invention, therefore, is to provide an improved method for providing a more reliable and effective sensing mark on a record card or sheet wherein the sensing mark comprises a layer of conductive material such as substantially pure powdered graphite in compressed concentrated form whereby the sensing mark is capable of maximum electrical conductivity.

A further object of the invention is to provide such a method and record card or sheet in which the sensing marks are made of compressed powdered graphite, or the like, provided on the record card or sheet in a manner whereby the marks are precise, well defined and of uniform consistency so that accurate sensing operations and uniform conductivity of said sensing marks is insured.

2

Another object of the invention is to provide a record card or sheet as described, and a method for forming sensing marks on the record card or sheet, as aforesaid, together with an overprinted protective coating for the sensing marks which prevents any smudge or smear thereof that might cause an inaccurate sensing operation.

A further object of the invention is for the provision of such a method and a record card or sheet provided with conducting sensing marks together with a protective coating on the marks in the form of a layer of frangible insulating material serving as a fraud preventing means to render the marks ineffective but capable of being selectively activated by mutilation or removal of the said insulating protective coating thereon; and, an additional object in this regard is directed to an improved fraud preventing arrangement of this character wherein such frangible insulating material or the like, is provided alone, without conductive marks, to define a group of spots or indicia that may be selectively mutilated according to a predetermined code or table to indicate any desired number in a manner which prevents fraudulent change or alteration of any such number.

Further objects and advantages, and other new and useful features of the invention will be readily apparent as the following description proceeds with reference to the accompanying drawings, for purposes of illustration but not of limitation, in which like reference characters designate like parts throughout, and in which:

Fig. 1 is a plan view of a record card or sheet in the form of a bank check provided with sensing marks in accordance with the invention by way of an example of a typical application of the invention.

Figs. 2, 3 and 4 are fragmentary sectional views of a card or sheet, as along line 4—4 of Fig. 1 on an enlarged exaggerated scale, and illustrate the successive steps in the method for providing the sensing marks in accordance with the invention, Fig. 2 showing the initial step in which an image or replica of the mark in adhesive is provided on the record card or sheet;

Fig. 3 illustrates the second step in the method in which powdered graphite is applied over the previously applied adhesive; and,

Fig. 4 shows the third step in the method wherein the conductive sensing mark is provided with a protective coating in the form of overprinting or the like.

Fig. 5 is a sectional view of Fig. 1 along line 5—5 showing the formation of a special group of

sensing marks with a frangible insulating coating which renders such marks ineffective but adapted to be selectively activated upon mutilation or removal of such insulating coating from the selected marks; and,

Fig. 6 is a similar sectional view of Fig. 1 along line 6—6 illustrating one of such insulated marks with the insulating coating mutilated or partially removed to render said mark effective as an electrical conductor forming part of a current path between a pair of electrical contacts.

Referring now, more particularly, to the drawings, Fig. 1 illustrates a typical application of the invention in which conductive sensing marks indicating the details of a transaction are provided on a tabulating card T in the form of a bank check according to the system disclosed in a prior application Serial Number 111,902 filed August 23, 1949, and issued as U. S. Patent Number 2,520,077 on August 22, 1950.

In accordance with the same general system, tabulating cards may be suitably provided with sensing marks for recording the details of any sale or other business transaction. In many instances, the tabulating cards are uniform as respects the sensing marks indicating the constant or source data of the transaction and, accordingly considerable savings are involved in providing the tabulating cards with preformed sensing marks indicating such constant or source data so that at the time of a transaction, only the sensing marks indicating the variable details of the transaction need be provided on the tabulating card.

In the case of a bank check, for example, the conductive sensing marks indicating the bank number and drawer's account number are advantageously preformed on the tabulating card together with those sensing marks indicating the number of the check. The check, accordingly, may be quickly completed for a transaction at any subsequent time merely by providing the sensing marks representing the required variable data such as the payee, amount and date of the check.

In the example of a bank check T, shown in Fig. 1, the upper area 10 is provided with printed characters and sensing marks reproduced from a printing identification plate as disclosed in the aforesaid prior application. Such a printing identification plate is adapted to reproduce the printed characters 11 disclosing the name and address of the payee together with an account number 12 assigned to such payee, as in the case of an employee of a company, for example. In a similar manner, there may be identified any other payee such as a creditor to whom checks are frequently forwarded in payment of periodic bills for goods or services rendered.

In the area 20, there are simultaneously printed the sensing marks 21 representing said account number 12. These sensing marks are provided in the area 20 at predetermined locations according to a code or table based on the order and value of each numeral or digit in the account number 12. In the present example, the account number 12 comprises nine digits and accordingly, the sensing marks 21 are shown reproduced in nine transverse columns in said area 20.

In each of such transverse columns, a sensing mark 21 representing a number or digit from 0 to 9, inclusive, is provided in a specific predetermined transverse location depending on the value of such numeral or digit. Preferably a column of similarly spaced identifying numerals 25 is

also printed on the card so that the sensing marks 21 may be easily read for verifying the same against the account number 12.

It will be understood, accordingly, that in the example of an account number 12, the first digit 5 thereof has its corresponding sensing mark 21 formed in the first transverse column in the area 20 and in the predetermined transverse position for the value five as indicated by such identifying numeral 25. The second numeral or digit of the account number 12 is a 3 and the sensing mark 21 for this digit is found in the second or next adjacent transverse column in the predetermined transverse position for the value three 15 as indicated by such identifying numeral 25. Likewise, the third numeral or digit of the account number is a 7 and the sensing mark 21 is located in the third transverse column in the area 20 and in the predetermined transverse position 20 for the value seven as indicated by such identifying numeral 25.

In a similar manner, the sensing marks 21 for the succeeding numerals or digits of the account number 12 find their places in the succeeding 25 transverse columns in the area 20 and in the predetermined transverse location for the particular numeral value thereof. A sensing mark 21 is thus provided for each numeral or digit of the account number 12 in accordance with its order 30 in the account number and the numeral value thereof. The sensing marks 21 thus formed are easily read when noted from left to right in Fig. 1, whereupon it will be seen that the order and value of said sensing marks 21 are identical to 35 the order and value of the respective numerals or digits of said account number 12.

The tabulating card T also includes a lower area 30 on which groups of other similar sensing marks 31a to 31d, inclusive, are printed in conjunction with the printed characters 11, 12 and 25 and the sensing marks 21. These groups of sensing marks 31a to 31d, inclusive, are of the same character as the sensing marks 21 and are provided in the same manner and relation on the 45 card area 30 according to the same general code or table based on the order and value of the digits in the numbers they represent. As shown, said groups of sensing marks 31a to 31d, inclusive, are selectively provided on the card in accordance 50 with the numeral values of the amount of the check, the bank number, the drawer's bank account number and the date of the check. Also provided with such selectively arranged sensing marks 31a to 31d, inclusive, are conventional numerals printed, written or otherwise provided on the tabulating card T on the side portion 37, for example, which indicate exactly the values of the numbers represented by said sensing marks 31a to 31d inclusive. Thus, it will be seen that in the 55 side area a indicating the amount of the check, the amount number \$375.92 is represented and indicated by the group of sensing marks 31a in the same order and of the same value as the respective digits of said amount number; likewise, the bank number in the side area b is represented and indicated by the group of sensing marks 31b; similarly the drawer's bank account number in the side area c is represented and indicated by the group of sensing marks 31c; and, the date of the check in the area d is represented and indicated by the group of sensing marks 31d.

In a similar manner, any other area of the card may be provided with sensing marks representing a number indicating a detail of the check or other document. In the area 40, for example,

the number of the check is represented and indicated by the similar selectively located group of sensing marks 41. It will be appreciated that the provision of the group of sensing marks 31a representing the bank number adapt such a tabulating card type of check shown for use in card sorting and tabulating machines in a bank clearing house and in the bank on which the check is drawn as well as in the accounting office of the company drawing the check. For further bank accounting purposes, such a tabulating card is readily prepared in the form of a deposit slip in which the constant or source data regarding the depositor is provided in the area 19 and the area 30 provided with similar sensing marks such as 31a representing the amount of the deposit, and sensing marks 31d indicating the date of the deposit, together with a group of similar sensing marks for the depositor's bank account number and likewise, for any other necessary or desirable detail regarding the deposit.

In the present example, the bank number, the drawer's bank account number and the number of the check are all predetermined known data, and accordingly, the groups of sensing marks 31b, 31c and 41, respectively, for these data may be preformed on tabulating cards prepared in quantity ready for use so as to provide considerable savings in the time and cost for completing such checks at the time they are prepared to be issued.

In accordance with the present invention, such preformed sensing marks 31b, 31c and 41 are provided on the tabulating cards in a permanent indelible form in which the graphite substance of the sensing marks is not subject to smudging or smearing that might result in inaccurate sensing operations, as aforesaid.

As illustrated in Fig. 2 the initial step in providing the sensing marks to be preformed on the tabulating card T involves the provision of images or replicas of said sensing marks in a coating or layer of adhesive 50. The adhesive may be applied in any suitable way as in the manner of a printing operation or by the use of a stencil and the adhesive sprayed or brushed onto the card through such stencil in the shape and size of the sensing marks to be provided. Preferably an adhesive is employed which will not cause any chemical change reducing the conductivity of the graphite substance of the sensing marks and, to the end, the use of a fine varnish as the adhesive 50 has been found highly satisfactory.

As seen in Fig. 3, following the application of the varnish 50 or other adhesive, there is applied the graphite 53 or other conductive material. Preferably, this is effected by a coating or layer of graphite 53 provided by powdered substantially pure graphite blown onto the previously applied adhesive 50 by a suitable blower 54 and the excess graphite removed by a suitable suction means 55. In this way, a major portion of the coating or layer provided by the particles of powdered graphite 53 adheres to the base layer of varnish 50 in substantially its pure state so that the sensing mark is capable of maximum electrical conductivity. In this condition, the sensing marks are admirably suited for accurate and reliable sensing operations, and, tabulating cards thus provided with sensing marks may be so used. However, in order to guard against any possible smudging or smearing of the graphite particles 53 of the sensing marks in the stacking, handling and repeated

use of the tabulating cards, it is preferable to provide the sensing marks with a protective coating 56 as shown in Fig. 4. Such a protective layer 56 is provided by a coating of any suitable substance so long as the same is sufficiently thin so as to permit conductivity between the graphite marks 53 and the associated electrical contacts which engage said marks.

In accordance with the present invention, 10 such a protective coating is provided by an ordinary overprinting operation in which any selected design or indicia may be printed on the record card or sheet over the sensing marks 53. At the same time, such overprinting serves to 15 compress the previously applied particles of powdered graphite forming said sensing marks 53 such that the sensing marks are finally provided in a highly compact, concentrated form adapted for maximum electrical conductivity.

20 The effect is such that the particles of graphite adhering to the adhesive in an image of the sensing mark are compressed in a continuous unbroken line as required to insure a proper electrical impulse. The overprinted protective 25 coating 56 not only protects the marks against smudging, smearing or removal of any portion of the marks in handling, stacking, etc., of the cards but also, shields the marks against wear 30 in a manner whereby the marks retain their original effectiveness even though used in a great many sensing operations.

35 A further advantage resides in the fact that the overprinted coating 56 may be provided in an opaque layer which completely conceals and hides the sensing marks in what may be termed a camouflage effect. This is particularly useful where it is necessary or desirable to guard against any fraudulent change in the location of certain of the sensing marks, such as the 40 sensing marks representing an exact sum of money, or a specific quantity of goods, for example. Also, such a camouflage effect is particularly advantageous in providing record cards in a neat, imperforate form with the overprinted 45 coating 56 defining attractive designs, advertising matter, and the like.

50 In addition, the overprinted protective coating 56 confines said graphite material 53 to the exact intended outline of the sensing marks and otherwise protects said sensing marks against 55 any smearing or smudging that might possibly result in inaccurate sensing operations. It has been found that such an overprinted protective coating 56 causes little or no increase in resistance in the electrical conductivity of the graphite 53 of the sensing marks thus provided, and that the sensing marks otherwise have substantially the same uniform conductivity through such protective coating 56.

60 It will be appreciated that the method of providing the sensing marks on an adhesive base 50 produces the marks in a sharp and precise form which also insures accurate and reliable sensing operations wherever intended. The 65 overprinted protective coating 56 may be applied only to the areas of the preformed sensing marks 31b, 31c and 41, or, to the entire area of the record card or sheet as desired. In the latter instance, the overprinted coating 56 does not affect the subsequent provision of the other sensing marks 21, 31a, and 31d for the variable details of the transaction inasmuch as these other sensing marks preferably are also provided in the same general method described wherein an 70 adhesive layer or coating of varnish 50 serves 75

as an excellent base which readily adheres to such previously applied overprinted protective coating 56.

Another feature of the invention of equal primary importance resides in the provision of the group of sensing marks 31a, or any other group of sensing marks representing variable data, in a manner whereby each of such marks includes a frangible top insulating coat or layer 60, Figs. 1, 5 and 6, which permits these marks to be selected as necessary to indicate any specific number, and guards against any fraudulent change of the selected marks representing such specific number.

In the present example, it will be understood that the marks 31a are those selected from this complete group for indicating any desired specific amount of the check. Each mark in this complete group is initially provided with a brittle, frangible insulating coating 60, Fig. 5, as in a small disc-like layer of material which is readily removable or mutilated by one's fingernail, a coin, or other implement. Such an insulating coating 60 is readily provided by a suitable powdered metal which when baked forms a brittle, frangible shell adhering to the card T. Preferably the insulating coating is formed on each of the marks in this group with a numeral indicating the individual values thereof, as illustrated in Fig. 1, to aid in the selection of those marks to be activated to indicate a desired number. This insulating coating 60 prevents any conductivity through the underlying conductive marks 53 but when mutilated or removed, renders any such mark effective to produce an electrical impulse in the usual manner.

Accordingly, in the same procedure described in the foregoing, any specific number may be indicated by this group of marks simply by mutilating or removing the insulating coating 60, Fig. 6, from the marks which must be selected to indicate such specific number. In the present example, the number represents the amount of the check \$375.92, Fig. 1, and the mutilated sensing marks 31a are those necessarily selected to indicate this specific amount, as previously described. The mutilation or removal of the insulating coating 60 from any of the other marks in this group would produce a readily visible change or alteration indicating that the check has been tampered with and should not be honored.

The insulating coating 60 is of such nature that it automatically crumbles and disintegrates when removed or mutilated and consequently cannot be replaced on the card in any manner resembling its original form. Thus, there is provided a most effective safeguard against fraudulent change in the amount of the check as originally made out inasmuch as any mark thus activated by the maker of the check cannot be effectively recovered with an insulating coating 60 as would be necessary in any attempt to substitute any other mark in the same transverse column, such as, for example, a mark indicating a higher numeral value for increasing the amount of the check.

It is to be understood that the general principles involved in providing a group of sensing marks with individual insulating coatings 60 for the purpose and uses just described are not limited, in any way, to the type of sensing marks referred to in the present disclosure, but rather, the use of such an insulating coating 60 on a

group of sensing marks is one of general utility and the same may be employed over any such sensing marks of any nature or of any material or substance for providing an electrical or electronic impulse.

In a still further relation, it is to be understood that such frangible insulating coatings 60 may be provided without sensing marks as a group of individual spots in a table similar to that illustrated in Fig. 1, and the same used in a manner whereby such spots may be selectively mutilated or removed to indicate the digits of a specific number or indicia or letters of a secret code word, or the like, for example. The procedure, accordingly, would be similar to that described wherein the brittle, frangible coatings 60 on the selected spots are mutilated or removed to indicate a specific number such as the amount of a check, for example, in order to guard against fraudulent alteration of the value of any such number, substantially as described.

While the invention has been described with specific examples, such examples are intended as illustrations only inasmuch as it will be apparent that various modification and deviations may be resorted to without departing from the spirit and scope of the invention. The present disclosure is, therefore, to be considered in all respects as illustrative and not restrictive, the scope of the invention being indicated by the appended claims rather than by the foregoing description, with all changes falling within the scope, meaning, and range of equivalency of the claims intended to be embraced therein.

What is claimed and desired to be secured by United States Letters Patent is:

1. An article comprising a sheet of material and electrically conductive marks located upon the surface of said sheet, and a layer of material over said electrically conductive marks adapted to disintegrate when mutilated or removed.

2. An article comprising a sheet of material and marks located upon the surface of said sheet in position to be engaged by correspondingly located electrical contacts, said marks comprising a layer of graphite adapted to form part of a current path between said contacts, and a layer of material over said layer of graphite adapted to disintegrate when mutilated or removed.

3. An article comprising a sheet of material and marks located upon the surface of said sheet in position to be engaged by correspondingly located electrical contacts, said marks comprising a layer of compressed powdered graphite adapted to form part of a current path between said contacts, and a layer of material over said layer of graphite adapted to disintegrate when mutilated or removed.

4. An article comprising a sheet of material and marks located upon the surface of said sheet in position to be engaged by correspondingly located electrical contacts, said marks comprising a layer of adhesive and a layer of compressed powdered graphite united to said adhesive and adapted to form part of a current path between said contacts, and a layer of insulating material over said layer of graphite adapted to disintegrate when mutilated or removed.

5. The method of producing an electrically conductive mark upon a record card or sheet which comprises, providing said mark in a layer

of conductive material on the card or sheet, and providing over said layer of conductive material a coating of material which renders said mark ineffective but which is adapted to be readily mutilated or disintegrated to activate said mark.

6. The method of producing an electrically conductive mark upon a record card or sheet which comprises providing said mark in a layer of graphite on the card or sheet, and providing over said graphite a coating of material which renders said mark ineffective but which is adapted to be readily mutilated or disintegrated to activate said mark.

WILLIAM H. WOLOWITZ.
